CHARACTER DISPLAY

William John Benmore, London, England, assignor to
Basaratta (M.A.D.E.) Limited, London, England

Filed Mar. 25, 1975, Ser. No. 561,773

Term of patent 14 years

Int. Cl. D20—02

U.S. Cl. D96—2

FIG. 1

FIG. 2

FIG. 3

FIG. 4

FIG. 5

FIG. 6

FIG. 7

FIG. 1 is a rear perspective view of a character display showing my new design, the character blocks being omitted;

FIG. 2 is a rear perspective view thereof with the character blocks in place except for one shown alongside the display for purposes of disclosure;

FIGS. 3 and 4 are respectively front elevational and top plan views thereof, the character blocks being omitted;

FIG. 5 is a cross-sectional view taken on line 5-5 of FIG. 4, looking in the direction of the arrows; and

FIGS. 6 and 7 are respectively side elevational and bottom plan views thereof, the character blocks being omitted in FIG. 6.

The character blocks are omitted in FIGS. 1, 3, 4, 5, and 6 for purposes of disclosure.

I claim:

The ornamental design for a character display, as shown and described.
